APPARATUS FOR BRAKING A THREAD

Vladimír Svatý and Lubomír Tatíček, Liberec, Czechoslovakia, assignors to Mira, zavody na pletene a stavkové zboží, národní podnik, Prague, Czechoslovakia

Application December 8, 1954, Serial No. 473,920

3 Claims. (Cl. 242—151)

The present invention relates to a method and an apparatus for braking a yarn or thread in a textile machine.

The braking of a yarn or thread in a textile machine may be accomplished directly, that is, by subjecting the thread to friction produced either by winding the yarn or thread around a yarn guide or by guiding the thread or yarn between two surfaces of brake discs pressed against each other, or indirectly bypassing a clamped or retained yarn or thread through rotary means, for instance, between a pair of rollers, braked in a suitable way.

The indirect braking action is unsuitable for a fluctuating velocity of the thread or yarn in view of the considerable inertia mass of the braking members.

The direct braking action, by winding the thread or yarn around a yarn guide, causes the initial tension of the thread, wound off a bobbin, to be increased and is therefore suitable for uniform materials only where the tension of the thread wound off a bobbin is not subject to fluctuations.

The most common braking means used are braking discs which, however, are objectionable because of the great inertia mass of the discs, which has an unfavorable effect on the operation of the apparatus whenever a knot passes between the discs, and also on account of an easy clogging of the braking mechanism when a yarn containing impurities is used, and still further because of considerable variations of the tension produced by one disc of the braking mechanism.

It has already been suggested to remove the above referred to drawbacks by the use of multiple brakes with a positive movement of the discs. The braking effect of every individual brake may in this way be reduced as many times as corresponds to the number of the brakes used, and also the fluctuations of the total braking effect may thus be reduced, but this process is uneconomical.

Braking devices are also known wherein the thread is braked by the sliding and rolling friction resulting from contact with a member of independent braking elements, for example, rollers or balls. Generally, such rollers or balls are arranged over the thread and gravitationally urged into contact with the latter. However, in that case there is no possibility for automatically removing, during operation, those impurities carried by the thread which eventually clog the spaces between the balls or rollers. Further, since the effect of gravity is relied upon for the braking of the thread, an adequate braking force can only be obtained through the use of relatively heavy braking elements, and such heavy elements produce severe shocks and stresses when knots or thickened areas of the thread are encountered. Further, the gravity influenced balls or rollers do not respond sensitively to variations in the thickness of the thread and, therefore, produce a non-uniform braking. In those cases where springs are employed to urge the balls or rollers against the braked thread, it is difficult to attain a precise setting of the springs, while the braking action or force increases with the deflection of the balls or rollers by the passage of a

2

knot or thickened portion of the thread and frequently causes thread-breakage.

The known drawbacks are eliminated according to the present invention by braking the thread or yarn by sliding and rolling friction in a plurality of points of contact independent from each other, using a device which according to the invention consists of a braking disc and a plurality of braking rollers attracted to the braking disc by means of a magnet. The resulting braking effect represents the sum total of a plurality of partial values so as to reduce the fluctuations of the tension of the thread to a minimum.

The accompanying drawing represents by way of example one embodiment of the apparatus according to the invention.

Fig. 1 is a side view of the apparatus of the invention, with parts broken away; and

Fig. 2 is a partly sectioned plan view, the section being taken in the plane of the line 2—2 of Fig. 1.

20 The braking disc 1 made of non-magnetic metal is mounted for rotation on a pivot 2 secured in a holder 3. A side member 4 made of antimagnetic material, for instance, fibers, is secured to the pivot 2, said side member 4 carrying another side member 6 connected thereto by bolts 5 and 5'. Steel braking rollers 8 are located in grooves 7, 7' of the side members 4 and 6, which rollers are provided with flanges 9 and biased against the braking disc 1 by means of a permanent magnet 10 mounted in the interior of the disc 1 and secured to the side member 4 by a screw 11. The screw 11 is adjustable in a groove 11' of the side member 4, thus permitting the adjustment of the position of the magnet 10 and in this way also of the braking effect.

25 The rollers 8 are secured against falling out by a loop 12 of steel wire.

Yarn guides 13, 13' are provided on the bolts 5, 5'.

The thread or yarn N is wound off the bobbin 14, guided through the yarn guide 13 between the disc 1 and the rollers 8 and passed through the yarn guide 13' in 30 the direction of the arrow S, for instance, to the winding-off and gauging device of a nozzle-operated weaving loom, not shown in the drawing.

35 The magnet 10 attracts the rollers 8 which press the thread N against the disc 1. When pulling the thread or yarn braked in this way, the rollers 8 and the disc 1 are set in rotation, thus preventing any clogging of the braking mechanism. The passage of knots is facilitated not only by the possibility of rotation of the rollers 8 and their small inertia mass but also by the fact that, on 40 lifting a roller 8 by a knot, the distance of the roller from the magnet 10 is increased and the braking effect reduced, just contrary to spring-operated braking devices in which upon passage of a knot the braking effect is increased, which usually causes the thread to break.

45 55 The intensity of the braking effect may be adjusted by the number of rollers 8 and by the change of the distance of the magnet 10 from the surface of the disc 1.

The braking rollers 8 placed next to each other form a grate, which allows the retained impurities to fall 60 through.

We claim:

1. An apparatus for braking a thread, comprising a rotatable braking disc, two side members, one at each side of the braking disc, a series of radial grooves in both 65 side members extending radially from outside to a point beyond the circumference of the braking disc, a plurality of magnetic braking rollers mounted in said grooves for rotation about axes parallel to the axis of rotation of said disc and in contact with the circumference of the 70 braking disc, a retaining member preventing radially outward removal of the rollers from said grooves, and a magnet mounted in the interior of the braking disc and

magnetically urging said rollers radially inward against the circumference of the braking disc, said magnet being adjustable radially with respect to said disc so as to change the attractive force exerted upon the rollers.

2. A device for braking a thread comprising a non-magnetic disc freely rotatable about a horizontal axis, fixed members at opposite sides of said disc, having aligned series of grooves extending radially outward from the periphery of said disc along a segmental portion of said periphery disposed below said axis of rotation of the disc, a plurality of magnetic rollers rotatably mounted in said grooves with their axes of rotation parallel to said axis of the disc and being movable radially in said grooves toward and away from the periphery of said disc, and a magnet within said disc acting through the periphery of the latter upon said rollers and magnetically urging the latter radially inward against said periphery of the disc so that a thread running between said periphery

and said rollers is braked by frictional and rolling contact therewith.

3. A device as in claim 2; wherein one of said fixed members has a slot therein extending radially with respect to said disc, and further comprising support means for said magnet movable along said slot to vary the proximity of said magnet to said rollers and to correspondingly adjust the force with which the latter are urged against said periphery of the disc.
